(57) **CLAIM**

The ornamental design for a motorcycle tank, as shown and described.

DESCRIPTION

The article in which the design is embodied comprises a vessel or reservoir for use upon a motorcycle for storing fluids associated with motorcycle engine function.

FIG. 1 is a plan view of the article in which the design is embodied.

FIG. 2 is a front elevational view of the article in which the design is embodied.

FIG. 3 is a side elevational view of the article in which the design is embodied; and,

FIG. 4 is a perspective view of the article in which the design is embodied.

Any broken-line illustration in the drawing disclosure is not a part of the design sought to be patented. The broken line boundaries along the bottom edge of the dash panel form no part of the claimed design.
